FIG. 10 is another view of FIG. 2 but shown without the broken lines illustrating portions of the graphical user interface, for clarity of illustrating the claimed design; FIG. 11 is another view of FIG. 3 but shown without the broken lines illustrating portions of the graphical user interface, for clarity of illustrating the claimed design; FIG. 12 is another view of FIG. 4 but shown without the broken lines illustrating portions of the graphical user interface, for clarity of illustrating the claimed design; FIG. 13 is another view of FIG. 5 but shown without the broken lines illustrating portions of the graphical user interface, for clarity of illustrating the claimed design. FIG. 14 is another view of FIG. 6 but shown without the broken lines illustrating portions of the graphical user interface, for clarity of illustrating the claimed design; FIG. 15 is another view of FIG. 7 but shown without the broken lines illustrating portions of the graphical user interface, for clarity of illustrating the claimed design; and, FIG. 16 is another view of FIG. 8 but shown without the broken lines illustrating portions of the graphical user interface, for clarity of illustrating the claimed design. The outermost broken line in each figure illustrates a display screen. The remaining broken lines in the figures illustrate portions of the graphical user interface. None of the broken lines form part of the claimed design.

The appearance of the user interface sequentially transitions between the images shown in FIGS. 1 and 2, FIGS. 3 and 4, FIGS. 5 and 6, and FIGS. 7 and 8. The process or period in which one image transitions to another image forms no part of the claimed design.
